UNITED STATES PATENT OFFICE.

POWERS WICKES, OF ALMONT, ASSIGNOR OF ONE-HALF TO CHARLES L. REXFORD, OF DETROIT, MICHIGAN.

WEATHER-STRIP.

SPECIFICATION forming part of Letters Patent No. 536,558, dated March 26, 1895.

Application filed January 24, 1895. Serial No. 536,060. (No model.)

To all whom it may concern:

Be it known that I, POWERS WICKES, a citizen of the United States, residing at Almont, in the county of Lapeer and State of Michigan, 5 have invented certain new and useful Improvements in Weather-Strips; and I do declare the following to be a full, clear, and exact description of the invention, such as will enable others skilled in the art to which it applies to make and use the same, reference being had to the accompanying drawings, and to the letters of reference marked thereon, which form a part of this specification.

This invention relates to certain new and 15 useful improvements in attachments for window frames and sashes, for the purpose of keeping out cold, dust and water, and the object of the invention is to produce a weather strip, which may be secured to the parting 20 strip of the frame having beads which are designed to slide in recesses in the faces of the sash, one cap or strip being provided for each sash.

To these ends and to such others as the invention may pertain, the same consists further 25 in the novel construction, combination and adaptation of the parts as will be hereinafter more fully described and then specifically defined in the appended claim.

30 I clearly illustrate my invention in the accompanying drawings, which, with the letters of reference marked thereon, form a part of this specification and in which—

Figure 1 is a perspective view of the sash 35 with the cap sliding in a groove thereof. Fig. 2, is a cross section through the parting strip, window frame and sash.

Reference now being had to the details of the drawings by letter, A designates the check rail of a window D the parting strip, 40 between the upper and lower sash. The upper and lower sashes are grooved out, as seen at D' and E is a weather strip, made of any suitable material, and is secured to the parting strip by any suitable means, preferably by 45 screws d, and the two laterally extending wings D² are designed to slide in the recesses or grooves D'.

It will thus be seen that a window frame and the sashes of a window equipped with my 50 improved weather strip, will effectually keep out the cold, water and dust, and the cap or strip secured to the parting strip, will also serve as a guide, while the sashes are being raised or lowered.

Having thus described my invention, what I claim to be new, and desire to secure by Letters Patent, is—

As an improved article of manufacture, a 60 weather strip E, of any suitable material, recesses on one side and having the beads D', the said recessed portion designed to be placed over and secured to a parting strip of a window frame, the window rails being grooved or recessed, and adapted to receive the said 65 beads and to slide thereon, substantially as shown and described.

In testimony whereof I affix my signature in presence of two witnesses.

POWERS WICKES.
